UNITED STATES PATENT OFFICE.

PAUL F. DUSHA AND ANTON FEYK, OF NEW YORK, N. Y., ASSIGNEES TO HOLUB DUSHA COMPANY, OF NEW YORK, N. Y., A CORPORATION OF NEW YORK.

BUTTON-EDGE-GRINDING MACHINE.

1,182,661.

Specification of Letters Patent.

Patented May 9, 1916.

Application filed August 11, 1915. Serial No. 44,887.

To all whom it may concern:

Be it known that we, PAUL F. DUSHA and ANTON FEYK, citizens of the United States, and residents of the city of New York, 5 borough of Manhattan, in the county and State of New York, have invented a new and Improved Button-Edge-Grinding Machine, of which the following is a full, clear, and exact description.

This invention relates to a machine for shaping and finishing the edges of pearl shell and other buttons.

The invention has for its general objects to provide a machine of the character referred to by which the edges of buttons can be ground or cut in various designs in a quick, simple and effective manner.

A more specific object of the invention is the provision of a button edge grinding machine which embodies a grinding wheel mounted on a movable frame which is oscillated by the joint action of a spring or equivalent means and a pattern which governs the peripheral shape of the button that 25 is being ground in the machine, the set of the grinding wheel carrying frame being adjustable so as to operate on button blanks of various diameters.

Another specific object of the invention is 30 the provision of a head stock having a spindle adapted to be clutched to the driving shaft automatically by longitudinally moving the spindle by the act of clamping a button blank between the spindles of the 35 head and tail stocks.

A further object is to provide a tail stock which is adapted to carry suitable work-holding means and which is urged by a spring or equivalent means into work-holding 40 position, there being a treadle-operated device for retracting the spindle of the tail stock so that the work can be removed from the machine.

With such objects in view, and others 45 which will appear as the description proceeds, the invention comprises various novel features of construction and arrangement of parts which will be set forth with particularity in the following description and 50 claims appended hereto.

In the accompanying drawings which 55 illustrate one embodiment of the invention and wherein similar characters of reference indicate corresponding parts in all the views, Figure 1 is a side view of the ma-

chine with a portion of the clutch broken away; Fig. 2 is a left-hand end view of Fig. 1; Fig. 3 is a plan view of the head stock portion of the machine; Fig. 4 is an enlarged sectional view of the spindles of the 60 head and tail stocks and the work-holding means; Fig. 5 is a detail sectional view of a modified form of work-holding means; Fig. 6 is a detail sectional view of the device for adjusting the position of the driving wheel; 65 Fig. 7 is a detail sectional view of the tail stock spindle adjusting means; and Fig. 8 is a view showing different forms of patterns for grinding the buttons.

Referring to the drawing, 1 designates 70 the base of the machine frame A, and rising from the base are bearing pedestals 2 and 3 for the head stock B, and bearing pedestals 4 and 5 for the tail stock C. On the pedestal 2 is a tubular bearing 5 for the 75 main driving shaft 6 on which is mounted a pulley 7 or equivalent means by which power is supplied to the machine. On the shaft is pinned a collar 8 which co-operates with the pulley 7 to prevent longitudinal 80 movement of the shaft, the inner end of the latter being provided with pinion teeth 9 that mesh with the teeth of the gear wheel 10. The tail stock comprises a spindle 11 journaled in the bearings 12 and 13 for 85 rotation and longitudinal movement, the longitudinal movement being comparatively slight for the purpose of unclutching or clutching the spindle from and to the driving shaft 6. For this purpose there is fastened to the spindle 11 a conical clutch member 14 which enters a hollow conical clutch member 15 which may be made integral with the gear 10, and interposed between these clutch members is a helical spring 16 90 that tends to throw the movable clutch member 14 to the right, Fig. 1, or out of engagement with the clutch member 15. The clutch is closed by the spindle 11 being moved to the left, this movement being effected by the 100 clamping of the work or button to be ground in the machine. The inner end of the spindle 11 is hollowed out so that in the bore 17 thereof a suitable chuck 18, Fig. 4, or 19, Fig. 5, may be inserted. The outer end 105 of the spindle carries a pattern 20 which may be of any desired form, as shown in Fig. 2, or Fig. 8, the pattern being provided with a central opening 21 through which extends a threaded reduced portion 110

or screw 22 on the spindle, and on this screw is a nut 23 which clamps the pattern against the shoulder or end face 24 of the spindle.

- 5 The edge of the button is shaped and finished by a grinding wheel 25 located adjacent the inner end of and behind the head stock spindle 11. This wheel is fastened to a shaft 26 that is journaled in bearings 27 and 28 of a frame D which is pivotally connected at its bottom to the base 1 by a horizontal pivot 29, whereby the cutter or grinding wheel will oscillate with respect to the button and thereby grind 10 the periphery to the desired shape. The oscillation of the frame D is effected by the joint action of a spring 30 and the pattern 20, the spring 30 being of the helical expansion type and having its front end connected 15 with a post 31 and its rear end connected with a tension-adjusting screw 32 carried by the frame D. The spring 30 is under a tension urging the frame D forwardly, but the rearward movement is effected by the 20 pattern 20 on the periphery of which runs a roller 33 carried by an arm 34 which is adjustably connected with the frame D. The arm 34 has an upwardly-extending handle 35 whereby the operator can conveniently 25 move the frame D. The adjustable connection between the frame D and the arm 34 is in the form of a screw 36 threaded in a stud 37 on the frame D, and the screw has a swiveled connection at 38 30 with the arm 34, so that by turning the screw the frame can be set forwardly or rearwardly so as to adjust the grinding wheel to operate on buttons of different diameters. The grinding wheel can be 35 axially adjusted by the means shown in Fig. 6. The shaft 26 passes through a sleeve or bushing 39 in the bearing 27, and on the outer end of this sleeve is threaded an adjusting ring 40, which, by being 40 turned, will move the sleeve to the right or left, the sleeve being prevented from turning by a set screw 41 engaging in a longitudinal slot 42 in the sleeve. A washer 43 is fastened to the outer end of the shaft 45 40 and engages one end of the sleeve 39 while the other end of the sleeve engages the driving pulley 44 fastened to the shaft 26. It will thus be seen that longitudinal movement of the sleeve 39 will effect a corresponding movement of the wheel shaft 26. Any suitable means may be provided to prevent the adjusting means 40 from moving axially. One side of the ring bears 50 against the bearing 27, and a lug 45 carried by the bearing engages the opposite side of the ring.

The spindle 46 of the tail stock is longitudinally slidable in the bearings 47 and 48. Surrounding the spindle is a helical compression spring 49 which has one end engag-

ing the bearing 48 and the other end engaging an adjustable collar 50 threaded on the spindle, whereby the spring urges the spindle toward the left. On the outer end of the spindle is a collar 51 to which is operatively connected the arm 52 of a bell-crank lever 53, the other arm 54 of this lever being engaged by a suitable operating means, such as a lever 55, that is fulcrumed at 56 on the base 1 of the machine, and which is connected by a rod 57 with a treadle or suitable means capable of being actuated by the operator, whereby the downward movement of the end 58 of the lever 55 will throw the opposite end 59 upwardly, whereby the bell-crank lever 53 will swing to the right and retract the spindle 46 of the tail stock against the tension of the spring 49. The position of the tail stock may be adjusted by turning the nut 60 on the screw 61 which is connected with and extends axially from the central reduced portion 62 of the spindle 46. The collar 51 surrounds the reduced portion 62 and the screw 61 passes through an opening 63 in the collar. The spring 49 maintains the surface 64 of the collar 51 against the adjacent bearing 48, and by unscrewing the nut 60 the spindle 46 will move toward the head stock while the reverse turning of the nut 60 will draw the spindle 46 to the right. By means of this adjustment various button or work-holding means may be used. As shown in Fig. 4, the tail stock spindle 46 is centrally bored to provide a chamber 65 for holding an auxiliary rotatable spindle 66 that rotates in a ball-bearing 67 and has its inner end engaging a thrust bearing 68. The upper end or head 69 of this spindle is bored and internally threaded to receive various devices employed for clamping and driving various forms and types of buttons, the edges of which are to be ground. A centering socket 70 is shown in Fig. 4 as threaded in the secondary spindle 66, and engaging in the socket is a center point 71 which has a pair of parallel pins 72 that engage in openings 73 of the button blank 74, such pins also engaging in openings 75 of the chuck member 76 threaded in the chuck 18. The chuck 18 has a conical shoulder 77 which is adapted to frictionally engage a corresponding surface 78 in the inner end of the head stock spindle 11. As shown in Figs. 1 and 2 the button 74 is clamped in the machine so as to rotate with the spindle 11, the spring 49 operating to clutch the chuck 18 to the spindle 11 and to hold the clutch members 14 and 15 in engagement. As the clutch is closed the buttons 74 will rotate with the spindle 11 and the edge of the button will be ground to conform in shape with the pattern 20 which controls the oscillatory movement of the grinding wheel frame, the grinding wheel being driven by a belt, not shown, passing 130

around the pulley on the grinding wheel shaft. When the edge of the button is ground the operator presses the treadle so as to move the spindle 46 to the right, whereby the chuck 18 is disengaged and the clutch members 14 and 15 disconnected. The finished button is now taken out by removing the center point 71, together with the button. A new button is replaced on the center point 10 and the latter applied to the chuck, the centering socket 70 being held back by the operator holding down the treadle. As soon as the centering point and treadle are in proper position the treadle is released so that the spindle 46 moves to the left and causes the point 71 to engage in the socket 70, the chuck 18 to frictionally engage the spindle 11, and the clutch members 15 and 16 to engage, whereby the spindle 11 is rotated and 20 with it the button 74, which is then ground by the grinding wheel.

For different types of buttons different forms of chuck constructions and coöperating holding means are employed. For instance, as shown in Fig. 5, the button 80 is of the type having a thread passage 81 parallel with the front face 82, and the chuck 19 has a socket 83 for receiving the shank 84 of the button, the socket 83 having 25 lugs 85 which engage the ends of the thread passage 81 so that the button will turn with the chuck 19. The coöperating holding device 86 that is carried by the tail stock spindle has rubber 87 which engages the 30 front face 82 of the button 81 to hold the button in driving engagement with the chuck 19. This chuck 19 is held in the spindle 11 by a set screw 88, Fig. 4.

From the foregoing description taken in 40 connection with the accompanying drawings, the advantages of the construction and method of operation will be readily understood by those skilled in the art to which the invention appertains, and while we have described the principle of operation, together 45 with the device which we now consider to be the best embodiment, we desire to have it understood that the device shown is merely illustrative and that such changes may be 50 made when desired as fall within the scope of the appended claims.

Having thus described our invention, we claim as new and desire to secure by Letters Patent:

55 1. A button edge grinding machine comprising a head stock having a rotatable spindle, means for fastening thereto a button to be ground, a pattern operatively connected to and rotating with the spindle, a grinding wheel, a frame movable back and forth and on which the wheel is mounted, an arm adjustably connected with the frame and operatively related to the pattern, whereby the latter moves the frame in one direction, 60 yielding means operating on the frame to

move the same in the other direction, and means for adjusting the position of the arm with respect to the frame, said frame and arm being mounted at the same side of the spindle as the grinding wheel. 70

2. A button edge grinding machine comprising a head stock including a rotatable spindle, means for clamping thereto a button to be ground, a pattern operatively connected to and rotated with the spindle, a 75 swinging frame mounted on the head stock, an arm also pivotally mounted on the head stock, a roller carried by the arm and engaging the pattern, a screw connected with the arm and frame for adjusting the position of the latter with respect to the spindle, yielding means acting on the frame for urging the same toward the spindle, and a grinding wheel carried by the frame, said frame, arm and screw being disposed at the 80 same side of the spindle as the grinding wheel. 85

3. A button edge grinding machine comprising a spindle for rotating the button to be ground, a driving shaft, a normally open 90 clutch adapted to be closed by longitudinal movement of the spindle for connecting the same with the driving shaft, a pattern connected with the spindle, a grinding wheel, a frame movably supporting the grinding 95 wheel, means whereby the movable frame is controlled by the pattern, a tail stock spindle coöperating with the first-mentioned spindle to clamp a button to be ground, means urging the tail stock spindle toward 100 the head stock spindle to move the latter and close the clutch, and means adapted to be manually actuated for retracting the tail stock spindle to release the button and to 105 permit the clutch to open.

4. A button edge grinding machine comprising a spindle for holding a button to be ground, a grinding wheel movable toward and from the spindle to grind the button, a carrier movably supporting the wheel, a 110 shaft movable in the carrier and to which the wheel is fastened, means for longitudinally adjusting the shaft in the carrier, a tail stock spindle coöperating with the first-mentioned spindle to clamp a button to be 115 ground, means urging the tail stock spindle toward the head stock spindle to move the latter and close the clutch, and means adapted to be manually actuated for retracting the tail stock spindle to release the button 120 and to permit the clutch to open.

5. A button edge grinding machine comprising a rotatable head stock spindle for rotating the button to be ground, a driving shaft, a normally open clutch between the 125 spindle and shaft and arranged to be closed by limited longitudinal movement of the spindle, a tail stock spindle coöperating with the first-mentioned spindle for clamping the button to be ground, means urging the tail 130

stock spindle toward the head stock spindle to clamp the button and to close the clutch, and means adapted to be actuated by the operator for retracting the tail stock spindle 5 for releasing the button and for permitting said clutch to open.

6. A button edge grinding machine comprising a rotatable head stock spindle for rotating the button to be ground, a driving 10 shaft, a normally open clutch between the spindle and shaft and arranged to be closed by limited longitudinal movement of the spindle, a longitudinally movable tail stock spindle, a spring urging the latter spindle toward the head stock spindle for gripping 15 the button between the spindles and for closing the clutch, and a treadle device for moving the spindle against the tension of the said spring for releasing the button and for 20 permitting the clutch to open.

7. A button edge grinding machine com-

prising a rotatable head stock spindle for rotating the button to be ground, a driving shaft, a normally open clutch between the spindle and shaft and arranged to be closed 25 by limited longitudinal movement of the spindle, a longitudinally movable tail stock spindle, a spring urging the latter spindle for gripping the button between the spindles and for closing the clutch, and means for adjusting the position of the tail stock spindle with respect to the head stock spindle. 30

In testimony whereof we have signed our names to this specification in the presence of 35 two subscribing witnesses.
